UNITED STATES PATENT OFFICE.

EDWARD ERICKSON, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

HEEL-ATTACHING MACHINE.

1,114,241.

Specification of Letters Patent.

Patented Oct. 20, 1914.

Application filed July 24, 1907. Serial No. 385,297.

To all whom it may concern:

Be it known that I, EDWARD ERICKSON, of Boston, in the county of Suffolk and State of Massachusetts, have invented certain new 5 and useful Improvements in Heel-Attaching Machines, of which the following is a specification.

This invention relates to machines for attaching heels to shoes and is adapted for use 10 with heels already loaded with nails.

The invention has the form of automatic mechanism which is adapted to be applied to the well known type of heel attacher termed the "National heeling machine."

15 The mechanism forming the present invention is adapted to receive loaded heels and heel lifts and carry them in turn to attaching position and to attach them and finally to assume a position in which new 20 heels and lifts may be applied with the greatest facility.

Referring to the drawings forming a part of this specification, Figure 1 is a front elevation of the upper portion of the type of 25 heeling machines, known as the "National," provided with the mechanism forming this invention. Fig. 2 is a right side elevation of the portions shown in Fig. 1. Fig. 3 is a top plan view of the same. Fig. 4 is a top plan 30 view of the work gage for holding the shoe in operative position. Fig. 5 is a left side elevation of that portion of the machine shown in Fig. 1 with the parts in different positions. Fig. 6 is a longitudinal section of 35 a heel-lift carrier. Fig. 7 is a cross section thereof. Fig. 8 is a longitudinal vertical section on the line 8—8 of Fig. 1. Fig. 9 is a section on the line 9—9 of Fig. 8. Fig. 10 is an inverted plan of a portion of Fig. 8. 40 Fig. 11 is a side elevation of the jack or work-support. Fig. 12 is a side elevation partly in section of the work gage for holding 45 the work in operative position. Fig. 13 is a rear elevation of the jack. Fig. 14 is a front elevation of a portion of the jack. Fig. 15 is a front elevation of the work gage. Fig. 16 is a top plan view of a portion of the 50 work gage.

The same reference characters indicate the 55 same parts wherever they occur.

Referring to the drawings only that portion of the machine is illustrated which is necessary in showing the operation of the mechanism forming this invention inasmuch 60 as this type of machine and its operation in

general is well known to those skilled in the art. That much of the National machine herein illustrated, comprises a bed plate 10 supported by upright sides 11 11. The sides 11 11 extend above the bed plate and form 60 bearings 12 12 for the upright rods 13 13 of a vertically movable driving head 14 connecting the upper ends of the rods. The rods are provided with collars 15 and helical springs 16 which serve to normally hold the 65 rods and driving head in an elevated position. The rods and driving head are adapted to be vertically reciprocated by means of which only the upper portion is herein illustrated, and which comprises a crank shaft 70 17, a pitman 18 of which the upper end is connected to the crank shaft as shown, and of which the lower end is connected in any suitable way to the rods 13 so that rotation of the shaft 17 may impart reciprocation to 75 the rods and the driving head 14. The work or shoe which is to receive a heel is supported on a suitable jack located on the bed plate 10 beneath the driving head 14.

The form of work rest, herein illustrated and indicated by the numeral 20, is mounted on an upright post 21 which is adjustably supported in a socket 22. The base of the socket has parallel flanges 23 23 which are adapted to slide in guides 24 24 secured upon 80 the bed plate 10, and extending from front to rear thereof. The jack by reason of its mounting is adapted to be manually moved to operative or attaching position directly under the driving head, or to a forward position, as shown in Figs. 2 and 3, in which a shoe may be more readily put on or taken off. The bed plate 10 is also provided with a work gage which is adapted to coöperate 85 with the jack in holding a shoe in operative 90 position. The work gage and jack are hereinafter described in detail.

Referring to Figs. 2, 5, 8 and 10, it will be seen that the driving head 14 is provided with a bracket or arm 25 extending from the 100 rear thereof. The arm 25 is provided with a bearing for a vertical rotary shaft 26 to the lower end of which is affixed a carriage 27 having a plurality of radial arms or bosses 28. The number of arms 28 shown 105 in this form of the invention is four and each is adapted to support an independently rotatable carrier adapted to carry either a loaded heel or a heel lift. Although there are four carriers illustrated upon the draw- 110

ings, the invention is not limited to that number for any convenient number of carriers may be provided without departing from the scope of the invention. The carriers are arranged on the carriage in a circular series so that when the carriage is rotated, as hereinafter explained, the carriers are moved successively into operative position relatively to the driving head, and then away from operative position to a position in which it is more convenient to supply to the carriers the loaded heels and heel lifts. The carriage 27 is rotated step-by-step and its rotation is interrupted whenever a carrier moves to operative position under the main body of the driving head. As the carriage 27 rotates step by step, the carriers move from operative position under the driving head toward the rear of the machine each carrier stopping in its rotation three times before completing a rotation about the axis of the carriage, and it is during one or more of these pauses that the carriers are in position to receive the heels and lifts.

The reciprocation of the driving head 14 is utilized to effect the step-by-step rotation of the carriage 27 by means of mechanism which causes the carriage to move during the upward stroke of the driving head and to remain stationary relatively to the head during the downward stroke of the latter. The upper end of the shaft 26 is provided with a bevel gear 29 affixed to the shaft by a set screw 30. The gear 29 intermeshes with a bevel gear 31 likewise affixed to a shaft 32 extending from front to rear through bearings in the driving head, and having on its front end, a toothed clutch member 33. The member 33 is adapted to coöperate with an annular toothed clutch member 34 affixed to a spur gear 35 loosely mounted on the shaft 32 between the member 33 and the driving head. The gear 35 intermeshes with an idle gear 36 mounted upon a stud 37 projecting forwardly from the driving head. The gear 36 also intermeshes with a stationary toothed rack 38 affixed to an arm or bracket 39 projecting upwardly from one of the side members 11.

As the driving head moves up and down relatively to the rack 38, the latter causes oscillation of the gear 35, the latter being free to turn about the shaft 32 as previously stated. The clutch member 34 is of the ratchet type and adapted to turn the clutch member 33 in one direction only, and for this reason, the member 33 is adapted to move longitudinally on the shaft 32 so as to permit the member 34 to turn in one direction without turning the member 33. The latter clutch member is splined to the shaft 32 by keys 40, and it is forced against the member 34 by means of springs 41 contained in sockets formed in the member 33, and abutting against a washer 42 affixed to the

forward end of the shaft. The inclination of the teeth of the clutch members is such as to impart a clockwise rotation to the shaft 32, and consequently rotation of the carriage 27 such as to cause the carriers thereon to move from right to left of the machine when viewed from the front. As hereinbefore stated, the carriage 27 in this embodiment of the invention is provided with four carriers and for this reason, the clutch members 33 34 are provided each with four equally spaced teeth. The range of reciprocatory movement of the driving head together with the relative size of the gear 35, is such as to cause the said gear to oscillate 80 through an arc of slightly more than 90° of a circle. It may be seen therefore that the oscillation of the clutch member 34 is such as to cause it to rotate the clutch member 33 step by step, each step being just 90° of a revolution. The gears 29 and 31 being of the same size, therefore transmit to the carriage 27 a step-by-step rotation corresponding exactly with that of the shaft 32, and consequently the carriage pauses in its 90 rotation as the carriers thereon are moved successively into operative position.

The carriers, hereinbefore referred to, comprise two heel carriers 43 43 and two heel-lift carriers 44 44. The heel carriers 95 43 are located at diametrically opposite points on the carriage 27, and the heel-lift carriers are likewise located at diametrically opposite points between the carriers 43. By means of this arrangement, the carriers form a circular series, of which the alternate members are heel carriers, and the intervening members heel-lift carriers. It therefore follows that, as the carriage is rotated step by step, first a heel carrier is 100 brought into operative position relatively to the head and then a heel-lift carrier is brought into operative position. In detail, each heel carrier comprises a rectangular block 45 having a cylindrical portion 46 110 bearing in a socket in the arm 28 of the carriage, and a cylindrical stem 47 having a bearing in a hub 48 of the carriage. The blocks 45 are adapted by reason of their bearing in the carriage to rotate relatively 115 thereto, each on an axis extending radially of the carriage. The cylindrical portion 46 of the block is provided with an annular peripheral groove 49 which is adapted to receive the end of a stud 50 screw-threaded in 120 the arm 28. The stud 50 permits free rotation of the block but prevents it from moving longitudinally in its bearing. Each block 45 has a socket 51 extending upwardly from its bottom face and adapted to receive 125 the stem of a driver plate 52. The driver plate is secured to the block 45 by a set screw 53 screw-threaded in the block and engaging the stem of the driver plate.

54 indicates a set of nail drivers affixed 130

to the driver plate 52 and projecting downwardly therefrom. The heel carrier plate 43 is affixed to one end of a stud 55 which extends through the stem of the driver plate 5 into the socket 51. The inner end of the stud 55 is provided with a washer 56 secured in place by a nut.

57 is a helical spring contained in the socket 51 and compressed between the end 10 wall of the socket and the washer 56. The spring 57 normally forces the washer against the inner end of the driver plate stem thereby normally holding the heel carrier plate 43 away from the driver plate 52. The plate 15 43 is provided with apertures 58 which register with the nail drivers 54 and which at all times inclose the lower ends of the drivers. The heel carrier is adapted to receive a loaded heel when it is diametrically opposite 20 the position it occupies when it is in position to attach a heel.

Referring to Fig. 8, the heel carrier shown in section is in operative or attaching position, and the carrier shown in elevation is in receiving position at a diametrically opposite point. A heel *a* adapted to be attached by this machine, is previously loaded with nails *b* whose heads project a suitable distance therefrom. The heel is preferably placed 25 upon the heel carrier when the latter is at rest in a position nearest the rear of the machine, as shown in Figs. 2, 3 and 8. In Fig. 2, a heel is shown directly above the heel carrier which is to receive it, the nails in the 30 heel and the apertures 58 in the heel carrier being correspondingly arranged so as to register one with the other. The nails inserted in the heel all have some slight inclination one to another, and by reason of this inclination, the nails when they are inserted in the apertures 58, bind sufficiently therein to 35 firmly hold the heel regardless of whatever position the carrier may assume. As an additional means for holding the heel more 40 firmly in position on the carrier, the latter is provided with a spring plate 59 having a series of teeth 60 adapted to engage the side of the heel. One end of the plate 59 is affixed to the driver plate 52, and the 45 other end of the plate 59 projects beyond the carrier so that it may be grasped and sprung so as to displace the row of teeth 60, which is approximately midway between the 50 ends of the plate 59 sufficiently to permit the application of the heel. When the plate 59 is released, the teeth 60 spring toward the 55 heel and hold it in place.

It will be observed that the heel carrier in 60 receiving position stands with its carrier plate 43 approximately uppermost, and that the carrier which lies directly under the driving head in driving position is turned so that the carrier plate 43 is at the bottom with its heel depending therefrom. The latter 65 position is necessary in order to attach a

heel to a shoe *c* mounted on the work rest 20, and the reason for turning the carrier about its individual axis to the first described position, is so that an attendant applying the heels to the empty carriers may see the apertures 58 and readily insert the nails therein. 70

Each carrier is provided with a gear 61 affixed to the stem 47, which gear intermeshes with a stationary gear 62 affixed to the bracket 25 of the head. The gears 61 as the 75 carriage 27 rotates, roll about the gear 62 describing a planetary motion and causing the carriers to rotate about their individual axes independently of the movement of the carriage. The gear 62 instead of having a 80 continuous series of teeth is provided with two separate series of teeth indicated at 63 and 64 in Fig. 10. The action of the teeth 63 and 64 relatively to the gears 61 is hereinafter described in detail. 85

The heel-lift carriers 44 hereinbefore mentioned, are mounted on rectangular blocks 65 similar to the heel carrier blocks 45. The blocks 65 are rotatably mounted in radial arms 28 of the carriage in precisely the same 90 manner as the blocks 45, and are likewise provided with planetary gears indicated at 66 67 in Fig. 10. The four gears attached to the two heel carriers and two lift carriers engage the gear 62 at four equidistant points 95 90° apart. The lift carrier plate 68 has dove-tail connection with a plate 69 which also has dove-tail connection with the block 65. The dove-tail connection between the plate 69 and the block 65 is adapted to permit the former to be moved relatively to the latter in a line transverse to the axis of the block, while the dove-tail connection between the plates 68 and 69 is adapted to permit the plate 68 to be moved transversely to 100 the movement of the plate 69, or parallel to the axis of the block 65. These two dove-tail connections are for the purpose of providing adjustment in either direction of the plate 68 as will be readily understood, and the two plates may be locked in any desired 105 position by means of set screws 70 and 71 illustrated in Figs. 6 and 7. The heel lift *d* is placed against the outer face of the plate 68 and held frictionally between lips 72 110 affixed to one edge of the plate and a movable lip 73 suitably mounted near the opposite edge of the plate. The movable lip 73 is adapted to engage the breast or straight edge of the lift and to press the rear or curved portion of the lift between and against the lips 72. A convenient means for accomplishing this is shown in Fig. 6 in which the lip 73 has an upturned flange 74 carrying a pin 75 which projects into a hole 76 extending through the plate 68 in a line 115 parallel to the median line of the lift *d*. The inner end of the pin 75 is connected to a spring 77 contained in the hole 76 and drawn thereby with yielding tension so as 120 125 130

to cause the lip 73 to coöperate with the lips 72 to frictionally hold a lift as explained.

Referring again to Fig. 10 in which the relative positions of the planetary gears are shown at A, B, C, D, it will be seen that all of these gears occupy the different positions successively as the carriage 27 is actuated. The planetary gear 66, belonging to one of the heel-lift carriers, is shown at position A, 10 in which position the carrier is adapted to receive a lift. This position of the lift carrier is also shown in Figs. 1, 3, and 5. The lift carrier is here at the left side of the machine.

15 The gear 61 belonging to one of the heel carriers and shown in position B in Fig. 10 indicates the position of the heel carrier when it is adapted to receive a heel. This position of the heel carrier is shown in Figs. 2, 3, 5 and 8, and the heel carrier is at the rear of the machine. The gear 67 belonging to the other lift carrier and shown at position C in Fig. 10, indicates the position at which the lift carrier pauses on its approach 20 to operative or attaching position. The gear 61 belonging to the other heel carrier and shown in position D in Fig. 10, indicates the operative or attaching position of the heel carrier. This position of the heel carrier is 25 shown in Figs. 1, 2, 5 and 8. A carrier after having attached either its heel or its lift, as the case may be, moves from position D to A causing its planetary gear to engage the series of teeth 63 on the gear 62. The number of teeth 63 relative to the number of teeth on the planetary gear is such as to impart to the latter a rotation of slightly less than 180°. During the next step in the rotation of the carriage in which the planetary 30 gear moves from position A to position B, the said gear leaves the series of teeth 63 and passes over a blank space between that series of teeth and the series of teeth 64. During this movement, the position of the 35 planetary gear relatively to its own axis remains unchanged. As the planetary gear moves from position B to position C, it engages the series of teeth 64 which impart to the said gear another partial rotation of 40 slightly less than 180°. Another blank space separates the teeth 64 and teeth 63 between positions C and D, and inasmuch as the planetary gear whose movement is being described, has so far received two partial rotations, each slightly less than 180°, it is clear 45 that some means must be provided to impart additional rotary movement to the gear and its carrier sufficient to complete one revolution about their individual axes, in order to 50 turn the carrier once more so that its heel or lift shall be on the under side thereof.

In Figs. 1 and 3, there is shown a plate 78 attached to the rear side of the driving head and having a rearwardly extending lip 55 adapted to be engaged by the inclined

edges of the carriers which lie above the horizontal plane of the under face 79 of the driving head. Each carrier as it approaches operative position relatively to the driving head, engages the plate 78 and is rocked thereby about its axis so that its top face assumes a horizontal position as it passes under the driving head. A revolution of the carrier about its axis is therefore completed, and its plane relatively to the plane of the under face 79 of the head is such that it engages the said face when in operative position. Subsequent downward movement of the head therefore exerts pressure directly upon the carrier which lies beneath it and no undue strain is imposed upon the carriage or other carriers when the operative carriage is attaching its heel or lift.

When a heel α is supported by a carrier as shown in Fig. 8, with the heads of the 85 nails occupying the apertures 58 in the carrier plate 43, the ends of the nails are adapted to abut against the ends of the drivers 54. With a shoe c supported in operative position upon the work rest beneath the driving head, the latter attaches the heel to the shoe by descending bodily together with the carriage 27 and all the parts mounted thereon. The heel engages the heel seat of a shoe just 90 an instant before the driving head reaches the lower extreme of its movement, and while the downward movement of the heel is arrested by contact with the shoe, the driving head continues to move a short distance toward the shoe thereby causing the driver plate 52 to approach the carrier plate 43 in 95 opposition to the tension of the spring 57 which normally holds the plate 43 away from the plate 52. This latter movement of the driver plate 52 causes the drivers 54 to 100 advance through the apertures 58 and to drive the nails through the heel and into the heel seat of the shoe, leaving the heads of the nails a short distance above the surface 105 of the heel for the purpose of subsequently receiving a heel lift. When the driving head 14 starts on its upward movement and moves far enough to raise the carrier plate 43 above the protruding heads of the nails, the clutch members 33 and 34, hereinbefore 110 described, coöperate with each other to advance the carriage 27 another step in its rotation. As the heel carrier, whose operation has just been described, leaves its operative 115 position under the driving head, a heel-lift carrier moves under the driving head with its upper face engaging the under face 79 of the head in the same manner as the heel carrier. A subsequent downward movement 120 of the driving head causes the lift carrier now in operative position, to descend toward the shoe and to spank the lift d upon the protruding heads of the nails in the previously attached heel.

The heel lift clamps 72 73 by reason of 125

their gentle frictional contact with the lift leave the latter on the heel without any appreciable tendency to pull it away from the nail heads. The driving head then rises 5 again causing the clutch members 33 and 34 to advance the carriage still another step in its rotation, and the heel carrier and the heel-lift carrier, whose operations have just been described, assume the positions indicated in Fig. 10 by B and A respectively. These two carriers are therefore in position 10 to receive another loaded heel and another lift, while their diametrically opposite mates are in position to attach their heel and lift 15 with which they are presumably provided. It will be observed that when the heel carriers are in operative position, their spring clamps 60 lie on the side toward the direction in which the carriage rotates, so that 20 when a heel carrier advances after having attached a heel, its clamp moves away from the heel and becomes disengaged therefrom without interfering with the heel which 25 has been attached.

It has already been shown that the carriers in moving from position A to position B are not affected by the stationary gear 62, the planetary gears during that portion of 30 their movement about the gear 62, being disengaged from the latter. By reason of being thus disengaged, the planetary gears and their carriers might become unduly turned if they were not in some way held and for 35 this reason, means is provided for maintaining each carrier in a position relatively to the carriage 27 to which it is moved by the series of teeth 63. This means is shown as comprising a pin 80 contained in a pocket 81 in each of the arms 28 of the carriage 27.

A spring 82 is placed in the pocket 81 behind the pin 80 and is adapted to force the pin against a shoulder 83 on the rotary block 40 mounted in the arm. That end of the pin 80 which engages the shoulder 83, is preferably tapered, and is adapted to be forced 45 into a depression 84 formed in the shoulder 83. The depression 84 is so located with relation to the block that it registers with and receives the end of the pin 80 when it is 50 moved to position A. The end of the pin 80 remains in the depression 84 from the time its carrier arrives at position A until it leaves position B. The teeth 64 on the gear 62 then impart additional rotation to the 55 carrier as previously described, and the pin 80 is forced back into its pocket 81 by the advancing of the depression in the shoulder 83, and the carrier is then securely held by the engagement of its planetary gear with 60 the teeth 64.

It has been hereinbefore explained how the clutch member 34 drives the clutch member 33 and shaft 32 in one direction only, and it is therefore preferable that some 65 means be provided to prevent the member

33 and the said shaft from undue rotation when the member 34 oscillates on its return stroke, and to prevent the shaft 32 from being unduly rotated in the direction in which it is driven. For the purpose of preventing 70 undue rotation of the shaft, the latter is provided with a circular disk 85 which is affixed thereto by means of a set screw 86, and which is adapted to be locked against undue rotation during the downward movement of the driving head. For this purpose, the disk is provided with four tapered holes 87 or one for each step of movement in 75 a revolution of the carriage 27. The holes 87 are adapted to successively receive the 80 tapered end of a pin or bolt 88 mounted in a bearing on the head and adapted to slide in and out toward and from the disk. The other end of the pin 88 is pivotally connected to the free end of an arm 89 which is 85 affixed to one end of a rock shaft 90 also mounted in bearings on the head. The other end of the rock shaft 90 is provided with a fixed arm 91 which, when it descends with the driving head, engages an upstanding projection 92 formed on a plate 93 attached by bolts 94 to one of the sides 11 of the frame.

95 is an arm pivotally mounted on the end of the rock shaft next to the arm 91. The 95 arm 95 is free to turn about the rock shaft and it is connected with the arm 91 by a spring 96. This spring serves two purposes of which one is to normally hold the arm 91 so as to effect the insertion of the bolt 88 100 into one of the holes in the disk 85. The other purpose of the spring 96 is to hold the free end of the arm 95 against a pin 97 protruding from the plate 93 as shown in Fig. 2. The plate 93 is provided with slots 98 105 through which the bolts 94 extend to secure the plate to the frame of the machine and by reason of these slots, the plate is capable of a slight vertical movement relatively to the frame. When the driving head descends, the arm 91 engages the upper end 110 of the projection 92 and is moved thereby so as to oscillate the rock shaft 90 and so to cause the arm 89 to withdraw the bolt 88 from the hole which it occupies in the disk 115 85. The arm 95 at the same time, descends with the driving head, being held against the pin 97 by means of the spring 96 as already stated.

99 is a depression formed in the edge of 120 the arm 95 which engages the pin 97, and it is adapted to register with the pin when the driving head is at its lowest position as indicated in Fig. 5. A shoulder 100 of the depression 99 then underlies the pin 97 and 125 engages the same when the arm 95 subsequently rises with the driving head. This shoulder engaging the under side of the pin 97 causes the pin and the plate 93 to rise a short distance with the driving head 130

thereby holding the arm 91 in the position which keeps the bolt 88 out of engagement with the disk 85, thereby leaving the disk free to rotate as the shaft 32 is advanced another step in its rotation. When the arm 95 has risen a short distance from its lowest position, an inclined portion 101 on the front edge of the arm 95 engages a fixed stop 102 attached to the bolts 94, and by means of the inclined face 101 the stop 102 displaces the arm 95 sufficiently to disengage the shoulder 100 from the pin 97, and the plate 93 is thereby released so that it may drop again to rest upon its bolts 94. As soon as the pin 97 and plate 93 are disengaged from the arm 95, the spring 96 actuates the arm 91 so as to cause the rock shaft 90 to project the bolt 88 once more toward the disk 85. The bolt therefore impinges against the face of the disk which is meanwhile being rotated until the succeeding tapered hole 87 registers with the bolt whereupon tension of the spring 96 causes the arm 91 to advance the bolt farther until it projects into the hole. The disk is therefore securely locked against rotation in either direction until the driving head again descends so far as to cause the arm 91 to be again displaced by the projection 92.

It has been hereinbefore stated that the support for the work rest 20 is movable in guides 24 on the bed plate 10 so that a shoe may be readily placed upon the work rest when the latter is in a forward position and so that the work rest may be moved toward the rear of the machine to a position under the driving head where it may receive a heel and toe lift. To go more into detail in the construction of the work support which is completely illustrated in Figs. 11, 13 and 14, it will be seen that the member 20 which somewhat resembles the form of a last, is attached to a head 105 mounted on the upper end of the post 21. The post is vertically movable in its support 22 and is provided with a stud 106 which occupies a longitudinal slot 107 formed in the support. The stud 106 prevents rotation of the post 21 but permits longitudinal movement thereof within a limited range. The lower end of the post 21 is screw-threaded and engaged with a nut 108 contained in the base of the support 22. By means of the nut 108, the post 21 may be raised or lowered and held in any desired position relatively to the support 22. The head 105 is rigid with the post 21, and is provided with a transverse partially cylindrical boss 109 which occupies a corresponding partially cylindrical depression in the under side of the work rest 20. By means of so mounting the work rest on the head 105, the work rest is capable of tilting relatively to the head so as to elevate more or less the heel or toe of a shoe supported thereon.

The work rest is held in any desired position by adjusting means comprising a rod or stem 110 of which one end is spherical as indicated at 111, and of which the other end is screw-threaded and adapted to receive a wrench by which it may be turned. The screw-threaded end of the stem extends transversely through a cylindrical nut 112 which is supported in the head 105 as on trunnions. The spherical end 111 is contained in a socket formed in the work rest 20 and confined therein by a plug 113. By means of the stem 110 having a ball and socket connection with the work rest and pivoted screw-threaded connection with the head 105, it may be seen that the work rest may be supported at any desired inclination relatively to the head. When the work rest is in its forward position, as shown by Figs. 2 and 3, a shoe 85 may be readily placed thereon and the whole may be moved manually to a position under the driving head. A suitable stop or work gage for determining the position of the shoe relatively to the driving head is illustrated in detail in Figs. 12, 15 and 16. For convenience, the work gage may consist of a fixed support 120 secured to the bed plate 10 and having a relatively fixed stop 121 adapted to limit the rearward movement of a shoe, and coöperative clamps adapted to receive the shoe between them and clamp it firmly upon the work support as shown in Fig. 4. The stop 121 is preferably adjustable toward and from the bed plate 10 and toward and from the work rest. For this purpose the stop is clamped by means of a bolt 122 to a head 123 formed on one end of a shaft 124 longitudinally movable in the fixed support 120. The head 123 is also provided with a pin 125 which extends parallel to the shaft 124 into a socket 126 formed in the support 120. The pin 125 is free to move longitudinally in its socket and it prevents the shaft 124 from turning in its bearing in the fixed support. The support is provided with an adjusting screw 127 mounted in a bearing at its rear end and provided with a hand wheel 128. The screw 127 is so mounted that it may be freely turned by means of the hand wheel, but is incapable of longitudinal movement. By means of the screw 127, the shaft 124 may be adjusted longitudinally in its bearing in the support 120 to any desired position. The bolt 122 which clamps the stop 121 to the head 123 extends through a vertical slot 129 formed in the stop. A tongue 130 is also formed on the stop 121 and occupies a vertical groove 131 formed in the head 123. By reason of the slot 129, the stop 121 may be raised or lowered relatively to the head 123 when the bolt 122 is released, and when the bolt is set up so as to clamp the stop 121 with its tongue 130 in 130

the groove 131, the stop is held rigidly against all movement.

132 132 are a pair of arms pivoted at 133 to the lower portion of the stop. The upper ends of the arms 132 are adapted to lie on the opposite sides of a shoe and they are provided with spring clips 134 134 which engage the sides of the shoe and clamp the same upon the work rest so as to firmly hold 10 the shoe in position during the operation of attaching a heel and lift. The spring clips 134 134 are affixed to plates 135 which have laterally extending slots 136 through which thumb screws 137 extend into the 15 arms 132 so as to bind the plates 135 to the arms at any desired position. The clips 134 may be adjusted toward and from each other so as to compensate for varying widths of shoes, or the arms 132 may be moved about 20 their pivots 133 toward or from each other for the same purpose. The arms 132 are provided with swiveled blocks 138 which are screw-threaded to receive independently 25 movable hand screws 139. The hand screws extend toward each other and into the stop 121. The inner end of each hand screw is provided with a ball 140 affixed to it, the two balls occupying an elongated aperture 141 formed in the stop which holds them together so that they abut against each other. By this means either or both of the arms 132, 30 may be individually adjusted so as to effect practically the same result as an adjustment of either of the plates 135. As indicated in 35 Figs. 4 and 16, the spring clips 134 are so arranged that when a shoe mounted on the work rest is moved rearwardly to operative position, the heel of the shoe enters between the clips thereby spreading them, and 40 finally abuts against the stop 121.

All of the details of the invention have been described and their operations explained separately, and it is therefore thought unnecessary to set forth the complete 45 operation of the machine as the latter can be readily understood by following the detailed descriptions. In practice, a machine of this character is provided with means preferably a treadle by which a continuously rotating shaft or some equivalent 50 may be controlled so as to impart to the driving head one downward and an upward stroke each time the treadle is depressed. The operation of removing a shoe from the work rest and placing a new one thereon requires a pause of such duration that an attendant at the rear of the machine has ample time in which to supply a loaded heel to one of the heel carriers and a lift 55 to one of the lift carriers. Then when a new shoe has been placed in operative position and the treadle depressed once so as to effect the attachment of the heel, the operator may immediately depress the treadle again 60 so as to effect the attachment of a lift

to the previously attached heel. It therefore follows that there need not be any prolonged pause between the attachment of a heel and the attachment of a lift, but that the longer space of time required for removing one shoe 70 and inserting another may be utilized by the attendant at the rear of the machine in supplying a heel and lift as described.

Having thus explained the nature of my said invention and described a way of constructing and using the same, although without attempting to set forth all of the forms in which it may be made, or all of the modes of its use, I declare that what I claim is:—

1. In a heel attaching machine, a driving head, a carriage movable thereon, and means on said carriage for grasping a heel element, said means being movable relatively to the carriage to one position for receiving the work, and to another position for depositing the work, such relative movement being rotary and said means being capable of turning in the same direction when moving to work-depositing position as when moving to work-receiving position. 90

2. A heel attaching machine comprising a rotatable carriage, a support therefor, a shoe support, one of said supports being movable toward and from the other, and nail-driving means mounted on said carriage, said means being rotatable relatively to said carriage and adapted to abut against said carriage support when in operative position to be braced thereby. 95

3. A heel attaching machine comprising 100 a carriage, a support therefor, a shoe support, one of said supports being movable toward and from the other, and a heel carrier mounted upon said carriage, said carrier being rotatable relatively to said carriage and 105 adapted to engage said carriage support to be positioned thereby relatively to said carriage in consequence of movement of said carriage to heel-attaching position.

4. In a heel attaching machine, a carriage, a heel-blank carrier and a heel-lift carrier both mounted on said carriage, said carriers being movable relatively to the carriage and movable independently of each other to one position for receiving the work 110 and to another position for depositing the work, such relative movement being rotary and said carriers being capable of turning in the same direction when moving to work-depositing position as when moving to work-receiving position. 115

5. A heel attaching machine comprising 120 a carriage, a support therefor, a shoe support, one of said supports being movable toward and from the other, and a plurality of carriers for heel elements mounted upon said carriage, said carriers being movable relatively to said carriage and adapted to engage successively a portion of said carriage support to be positioned thereby in 130

consequence of movement of said carriage relatively to said carriage support.

6. A heel attaching machine comprising a reciprocating head, a rotatable carriage mounted on the head, a circular series of individually rotatable blocks mounted on the carriage, a set of nail drivers on each alternate block, a heel carrier on each of said alternate blocks, a heel-lift carrier on each intervening block, means for rotating the carriage step by step so as to move said carriers successively into attaching position, and means for rotating said blocks.

7. A heel attaching machine comprising a reciprocating head, a rotatable carriage mounted on the head, a heel carrier mounted on the carriage and rotatable about an individual axis, means for rotating the carriage step by step so as to move the heel carrier alternately into and out of attaching position, and means for rotating the carrier step by step about its individual axis, one revolution for each revolution of the carriage about its axis.

8. A heel attaching machine comprising a reciprocating head, a rotatable carriage mounted on the head, a series of heel carriers and heel-lift carriers arranged alternately on the carriage in a circle about the axis of the carriage, each carrier being independently rotatable about an individual axis, means for rotating the carriage step by step so as to move the carriers successively into attaching position, and means for imparting intermittent planetary rotation to each of said carriers so as to cause it to turn about its individual axis.

9. A heel attaching machine comprising a reciprocating head, a rotatable carriage mounted on the head, a series of blocks arranged on the carriage in a circle about the axis of the carriage, each block being independently rotatable on its own axis, a set of nail drivers on each alternate block, means on each of said alternate blocks for receiving, carrying and attaching a loaded heel, means on each intervening block for receiving, carrying and attaching a heel lift, means for rotating the carriage step by step so as to move the blocks and carrying means successively into attaching position, and means for rotating the blocks intermittently about their own axes so as to turn them successively to receiving position and back to attaching position relatively to the carriage.

10. A heel attaching machine comprising a reciprocating head, a rotatable carriage mounted on the head, a plurality of blocks mounted on the carriage and arranged in a circular series concentric to the axis of the carriage, and each adapted to rotate on an axis radial to the axis of the carriage, means for rotating the carriage step by step so as to move the blocks successively into juxtaposition relatively to the head, a series of

carriers, one on each block, each adapted to hold either a loaded heel or a heel lift, a rotary gear affixed to each block concentric to its axis, and a gear affixed to the head and having teeth adapted to be engaged by said rotary gears and to rotate said gears when the latter are moved about the axis of the carriage.

11. A heel attaching machine, comprising a rotatable carriage, a support therefor, a series of carriers for heel elements mounted upon said carriage, said carriers being rotatable relatively to said carriage, said carriers being movable successively to operative position by rotation of said carriage in one direction, gears compounded respectively with said carriers, and a gear affixed to said support to coact with said carrier gears to turn said carriers with relation to said carriage.

12. A heel attaching machine comprising a reciprocating head, an intermittently rotatable horizontal carriage mounted on the head, an upright having a fixed gear rack, a gear mounted on the head and adapted to roll on the rack in intermeshed relation therewith, a gear mechanism interposed on the head between said gear and carriage and adapted to be actuated by reciprocation of the head so as to impart to the carriage a step-by-step rotation in one direction, and a circular series of carriers mounted on the carriage and means for causing them to pause successively at the same points when the carriage is actuated.

13. In a heel attaching machine, a carriage, a series of work carriers mounted on said carriage so as to be rotatable relatively to the carriage, and means for intermittently rotating said carriers independently of each other so that each will be alternately in two different positions with relation to the carriage, one of which positions is to facilitate loading the carrier and the other to place the work carried thereby in operative position.

14. In a heel attaching machine, a shoe support, a vertically movable head movable toward and from said support, a carriage supported on said head and movable about an axis parallel with the lines of movement of said head, means operated automatically by the movement of said head for automatically rotating said carriage unidirectionally with a step-by-step movement, and a carrier on said carriage and movable therewith from a position out from said head to a position under and abutting against said head in alignment with the shoe support.

15. In a heel attaching machine, a shoe support, a holder for a heel member, a carriage for said holder, said carriage being movable for moving said holder to and from the shoe, said holder being rotatable with relation to the carriage, and means for im-

parting a complete rotation to said holder relatively to the carriage for each cycle of the carriage.

16. A heel attaching machine, comprising a rotatable carriage, a support therefor, a shoe support, one of said supports being movable toward and from the other, the axis of said carriage being parallel to the line of relative movement of said supports, a series 5 of heel-element carriers mounted on said carriage and being rotatable relatively to said carriage, each of said carriers having a device whereby it may be turned relatively to said carriage, and means on said carriage 10 support for coacting with said devices to turn said carriers, said carriers being movable to carry said devices successively into engagement with said means.

17. In a heel attaching machine, a shoe 20 support, a series of holders for heel elements, a carriage for said holders whereby they are moved successively into coöperative relation with the shoe support, each of said holders being rotatable with relation 25 to the carriage, and means for imparting a complete rotation to each of said holders for each cycle of the carriage.

18. In a heel attaching machine, a shoe 30 support, a rotatable carriage, a series of holders on said carriage for holding heel members, said holders being rotatable with relation to the carriage, means for rotating the carriage step by step to place the holders successively in coöperative relation to the 35 shoe support, and means for imparting to each holder a complete rotation for each cycle of the carriage.

19. In a heel attaching machine, a shoe 40 support, a rotatable carriage, a series of holders on said carriage for holding heel members, said holders being rotatable with relation to the carriage, means for rotating the carriage step by step to place the holders successively in coöperative relation to the 45 shoe support, and means for rotating said holders intermittently with relation to the carriage, said means imparting a complete rotation to each holder for each cycle of the carriage.

50 20. In a heel attaching machine, a shoe support, a rotatable carriage, a series of holders on said carriage for holding heel members, said holders being rotatable with relation to the carriage, means for rotating the carriage step by step to place the holders successively in coöperative relation to the 55 shoe support, and means for rotating the holders intermittently with relation to the carriage, said means having provision for letting each holder remain stationary with relation to the carriage throughout one step of movement in each cycle of the carriage, said means imparting a complete rotation to each holder for every cycle of the carriage.

60 21. In a heel attaching machine, a shoe

support, a rotatable carriage, a series of holders on said carriage for holding heel members, said holders being rotatable with relation to the carriage, means for rotating the carriage step by step to place the holders successively in coöperative relation to the shoe support, and means for imparting a complete rotation to each holder for each cycle of the carriage, said means having provision for interrupting the relative rotation of the holders successively throughout successive rotative steps of the carriage. 70 75

22. In a heel attaching machine, a shoe support, a vertically movable head, one of said parts being movable toward and from the other, an intermittently rotatable horizontal carriage on the head, a plurality of carriers for heels and heel lifts mounted on the carriage and movable in a plane transverse to the path of movement of said movable part so as to successively occupy a position in alinement with the shoe support, a gear mechanism connected with said carriage, a circular disk mounted on the shaft of said gear mechanism adjacent to and movable with the carriage and having apertures corresponding in position to the positions of the carriers on the carriage, a spring-pressed bolt mounted on the head for entering an aperture in the circular disk 80 and locking the circular disk when the corresponding carrier is in alinement with the shoe support, and means for automatically operating said bolt to lock and unlock said disk. 85 90 95

23. In a heel attaching machine, a shoe support, a vertically movable head, one of said parts being movable toward and from the other, an intermittently rotatable horizontal carriage on the head, a series of carriers on the carriage movable therewith in unison and adapted to receive in one position heels or heel lifts as the case may be, and to move successively from receiving to attaching position relatively to the head 100 and shoe support, a gear mechanism connected with the head, and a circular disk adjacent to and movable with the carriage and having a series of apertures corresponding in number and position to the carriers 105 on the carriage, a spring-pressed bolt on the head and adapted to abut against the circular disk and to enter an aperture and lock the circular disk when the corresponding carrier arrives at its attaching position, and automatic means for moving the bolt out of the aperture to permit subsequent movement of the carriage. 110 115

24. In a heel attaching machine, a shoe support, a vertically movable head movable toward and from said support, a carriage supported on said head and movable about an axis parallel with the lines of movement of said head, mechanism for imparting a step by step unidirectional rotation to said 120 125 130

carriage, automatic means for locking and unlocking said carriage, and a plurality of equally spaced carriers arranged in radii of said carriage and adapted to register successively with said shoe support and said head when the carriage is locked.

25. In a heel attaching machine, a head, a shoe support, one of said parts being movable toward and from the other, a carrier on said head movable in a plane at right angles to the path of movement of the movable part, and means for automatically operating said carrier, comprising a rack and a pinion, one of the last-mentioned elements being operatively connected to said carrier.

26. In a heel attaching machine, a head, a shoe support, one of said parts being movable toward and from the other, a carrier on said head movable in a plane at right angles to the path of movement of the movable part, means for automatically operating said carrier, and means for automatically reversing said carrier.

27. In a heel attaching machine, a shoe support, a head movable vertically toward and from said support, a main frame having guides for said head, a carriage on said head movable about a pivot parallel with the path of movement of said head, a stationary rack on said frame, a gear intermeshing with said rack and mounted on said carriage to move therewith, and a clutch connecting said gear and said carriage to effect unidirectional step by step rotation of said carriage as said head reciprocates.

28. In a heel attaching machine, a shoe support, a head movable vertically toward and from said support, a main frame having guides for said head, a carriage on said head movable about a pivot parallel with the path of movement of said head, a stationary rack on said frame, a gear intermeshing with said rack and mounted on said carriage to move therewith, a clutch connecting said gear and said carriage to effect unidirectional step by step rotation of said carriage as said head reciprocates, and alternating carriers for heels and lifts respectively movable with said carriage in its rotative movement.

29. In a heel attaching machine, a shoe support, a holder for a heel member, a carriage for said holder, said holder being rotatable with relation to its carriage, means for actuating the carriage intermittently to move the holder to and from co-operative alignment with the shoe support, and means for rotating said holder intermittently in one direction relatively to the carriage to place the holder in one position to receive a heel

member, and in another position to present the heel member to the shoe.

30. In a heel attaching machine, a shoe support, a rotatable carriage, a plurality of heel-blank holders and a plurality of heel-lift holders disposed in a concentric series on said carriage, said holders being rotatable with relation to the carriage, means for rotating the carriage step by step to place the holders successively in operative relation to the work support, and means for imparting a complete step-by-step rotation to each holder relatively to the carriage for each cycle of the carriage, whereby the positions of the holders are changed to facilitate their being loaded.

31. In a heel attaching machine, a shoe support, a rotatable carriage, a holder mounted on said carriage for holding a heel blank, a heel-lift holder mounted on said carriage, said holders being rotatable step by step with relation to said carriage, means for turning said carriage step by step in one direction to place said holders successively in co-operative relation to the shoe support, and means for rotating said holders intermittently in one direction with relation to the carriage to place them successively in work-attaching position and in a different position for receiving the work.

32. In a heel attaching machine, a rotatable carriage, a plurality of holders for heel members mounted thereon so as to be rotatable about axes which are radial to the carriage axis, said holders having means for holding heel members, means for rotating the carriage step by step to move the holders successively into working position, and means for turning the holders step by step about said radial axes to facilitate loading the holders.

33. In a heel attaching machine, a rotatable carriage, a plurality of holders for heel members disposed thereon in a circular series, means for mounting said holders so that they are rotatable relatively to each other about axes which intersect the carriage axis, a mutilated gear, and gears secured respectively to said holders in position to co-operate with said mutilated gear, and means for rotating said carriage step by step, said gears being adapted to rotate the holders intermittently.

In testimony whereof I have affixed my signature, in presence of two witnesses.

EDWARD ERICKSON.
